UNITED STATES PATENT OFFICE.

WILLARD HOWARD WOODS, OF DYERSBURG, TENNESSEE.

RAIN GUARD FOR WINDOWS.

Application filed September 15, 1924. Serial No. 737,825.

To all whom it may concern:

Be it known that I, WILLARD H. Woods, a citizen of the United States, residing at Dyersburg, in the county of Dyer and State 5 of Tennessee, have invented certain new and useful Improvements in Rain Guards for Windows, of which the following is a specification.

This invention relates to a rain guard for 10 windows, and has for its principal object to provide a simple and efficient means whereby the lower sash of a window may be kept open for obtaining the proper ventilation of the room, yet preventing any possibility of 15 rain entering the room through the open window.

Another object of the invention is to provide a rain guard of the above mentioned character, which is of such construction as 20 to enable the same to be readily and easily secured in position on a window frame, and will not, in any way, interfere with the opening or closing of the lower window sash.

25 A still further object of the invention is to provide a rain guard of the above mentioned character, which may be readily and easily folded up, when not in use, the device being further inexpensive, strong and durable.

Other objects and advantages of this invention will become apparent during the course of the following description.

In the accompanying drawing, forming a 35 part of this specification, and in which like numerals designate like parts throughout the same:

Figure 1 is a front elevation of the rain guard embodying my invention, and

40 Figure 2 is a vertical sectional view, taken approximately upon the line 2—2 of Figure 1.

In the drawing, wherein for the purpose of illustration is shown the preferred embodiment of my invention, the numeral 1 designates generally the rain guard embodying my invention, the same comprising a substantially rectangular shaped piece of waterproof fabric. The waterproof fabric 45 or cloth is provided with the hems 2 and 3 respectively, which extend upwardly from the lower corners of the fabric in converging relation, whereby the front apron 4 and the side or end aprons 5 and 6 respectively 50 are formed.

Disposed in each of the hems is an elong-

gated rod, the ends of which terminate in suitable eyes 7 and 8 respectively. The upper edge of the water proof fabric is also provided with a hem 9 for the upper edge 60 of the front apron 4, the upper edges of the side apron being also provided with hems, such as are shown at 10 and 11 respectively. The adjacent ends of the hems formed in the waterproof fabric are cut 65 away, as clearly illustrated in Figure 1 of the drawings.

A reinforcing rod is disposed within the hem 9 at the upper edge of the front apron 4, and is designated at 12 in the drawings, 70 the respective ends of the reinforcing rods being provided with eyes 13 and 14 for interconnection with the eyes 7 formed on the upper ends of the reinforcing rods, which are disposed in the hems 2 and 3. 75 Reinforcing rods 15 and 16 are disposed within the hems 10 and 11 respectively, the forward ends of the last mentioned reinforcing rods being provided with eyes 17 and 18 respectively for interconnection with the adjacent eyes of the reinforcing eyes mounted in the hems 2, 3, and 9, as is clearly 80 illustrated in Figure 1.

The opposite ends of the reinforcing rods 85 15 16 terminate in the hooks 19 and 20 respectively, and these hooks engage in suitable eyes 21 arranged on the inner face of the sides of a window frame A. The eyes 8 formed on the lower ends of the reinforcing rods and disposed within the hems 2 and 3 90 have associated therewith the snap hooks 22 which engage the eyes 23, also supported on the inner face of the opposite sides of the window frame A, adjacent the sill B.

95 With the parts arranged as shown in Figure 1 of the drawings, the lower edge of the front apron 4 will extend across the lower portion of the inside of the window frame, while the upper edge of the front apron will be spaced from the window frame 100 and held in such position by means of the side aprons 5 and 6 and the reinforcing rod supported in the upper edges thereof.

The provision of a rain guard of the above 105 mentioned character enables the lower sash C of the window, to be raised for obtaining the proper ventilation, yet preventing any possibility of rain entering the room through the open window. The rain guard will furthermore be capable of detachment 110 from the window frame, when it is not desired to use the same, and may be folded and

stored away in a minimum amount of space. When in position on the inside of a window, the rain guard will not interfere with the opening or closing of the sash.

5 While I have shown the preferred embodiment of my invention, it is to be understood that various changes in the size, shape and arrangement of parts may be resorted to, without departing from the spirit of the invention and the scope of the appended claims.

Having thus described my invention, what is claimed is:

1. A rain guard for windows including a 15 piece of water proof fabric, a pair of reinforcing members attached to the fabric and converging upwardly from the lower corners thereof and terminating at their upper ends in spaced relation to each other at the 20 upper edge of the fabric, a third reinforcing member extending along the upper edge of the fabric and attached thereto and having its ends loosely attached to the upper ends of the first mentioned pair of reinforce-

ing members, and a further pair of reinforcing members attached to the upper edge of the fabric beyond the third reinforcing member above mentioned and loosely connected to the third reinforcing member. 25

2. A rain guard for windows including a 30 piece of water proof fabric, a pair of reinforcing members extending upwardly from the lower edge of the fabric and converging toward each other and terminating in spaced relation to each other at the upper edge of the fabric, a third reinforcing member attached to the upper edge of the fabric and loosely connected to the pair of reinforcing members first mentioned, the connecting 35 ends of the reinforcing members being provided with engaged eyes, and an additional pair of reinforcing members having eyes engaged with the aforementioned eyes and fixed to the upper edge of the fabric beyond the third reinforcing member and terminating in hooks. 40 45

In testimony whereof I affix my signature,
WILLARD HOWARD WOODS.
